JOSEPH STEIDL, OF BRONX, NEW YORK

COMBINATION TABLE

Application filed May 18, 1931. Serial No. 538,224.

The objects of this invention are to provide a table construction, which may be readily converted for different purposes, for example, be transformed from a coffee table to a dining 5 table, or vice versa, be easily raised and lowered to different heights and which will be practical and desirable in all respects.

The foregoing and other desirable objects are attained by the novel features of construction, combinations and relations of parts hereinafter described, claimed and illustrated in the accompanying drawings.

The drawings show by way of illustration one practical embodiment of the invention, it 15 being understood that the structure may be modified and changed as regards this disclosure without departure from the true spirit and broad scope of the invention.

Fig. 1 is a partially broken and sectioned 20 side elevation of a table embodying the invention; Fig. 2 is a partial bottom plan and broken sectional view looking upward as on line 2—2 of Fig. 1; Fig. 3 is an enlarged broken and part sectional face view illustrating the ratchet mechanism; Fig. 4 is a sectional detail as on line 4—4 of Fig. 3; Fig. 5 is a broken perspective and part sectional 25 view of the ratchet construction; Fig. 6 is a broken detail of the spring pawl construction; Fig. 7 is a broken perspective detail of 30 the special holding pawl; Fig. 8 is a fragmentary sectional detail illustrating the pawl as let into the ratchet to its full extent to lock the table at a desired height, this view 35 being taken as on line 8—8 of Fig. 3.

Referring first to Figs. 1 and 2, it will be seen that the pedestal of the table is telescopically adjustable by the provision of a hollow base portion 9, having suitable feet 40 10 for engagement with the floor or supporting surface and a post or standard 11, slidably engaged in the hollow base and carrying the table top 12. The hollow base and the standard portion therein are shown as of 45 rectangular cross-section and the fit is such that the standard will slide vertically in the base, smoothly and easily, but without wobbling.

To enable easy adjustment, the weight of 50 the table top and standard is counterbal-

anced by a spring 13, located in the hollow base and operating against the closed lower end 14 of the hollow standard.

For securing the table in various positions of vertical adjustment, a special pawl and ratchet connection between the standard and base is provided. The ratchet which is shown as formed in or carried by the side of the post or standard, consists in the illustration of a set of upwardly faced ratchet teeth 15, having at the sides of the same abruptly shouldered seats 16 and the pawl is illustrated as carried by the base and as consisting of a spring strip 17, having at its upper end a downwardly faced tooth or lug 18 for engagement with the upwardly facing ratchet teeth and locking lugs 19 at opposite sides of the pawl tooth to interlock with the holding seats 16.

For controlling the pawl, a stud 20 is shown 70 projecting from the back of the pawl out through a guide 21, said stud having a head 22, providing an operating handle and beneath that, a rotatable button 23, having outstanding wings or lugs 24, which, when the button is turned as in Fig. 8, will drop into notches 25 in the guide to let the pawl interlock with the seats 16 or, when the button is turned as in Fig. 4, will engage the end of the guide 21, to hold the pawl partially retracted, with lugs 19 clear of recesses 16 and the pawl thus free to yield to a downward adjusting movement of the table top.

It will be clear from what has been said 85 that the pawl can be entirely retracted from engagement with the ratchet by drawing outward on the handle disc 22 as shown in the broken lines in Fig. 8, whereupon the standard carrying the table top will rise 90 under the lifting force of the spring 13. This upward movement may be readily controlled by pressure of one hand on the table top, while the other hand is holding the pawl withdrawn. When the desired height is 95 reached, the pawl may be dropped back into interlocked engagement with the ratchet as in the solid lines, Fig. 8, at which time, the table top is locked against movement either 100 up or down and the turn button is held

against movement by the interlocking engagement of the webs or pins 24 in the notches 25.

A scale such as indicated at 26, in Fig. 1, 5 may be provided on the standard or center leg of the table to aid in securing the desired 10 adjustments of the table. Thus, this may be a scale laid off in inches, or it may have simple 15 markings, registering with the base to indicate the proper heights for tea or coffee table, 20 card table, dining table, or other desired uses.

Upon partially retracting and turning the 15 button 23, to bring the lugs 24 over the end of 20 guide 21, as in Figs. 3 and 4, the pawl will still hold the table down to the desired level but, with the locking lugs 19 freed of the 25 locking recesses 16, it will yield outward under push of the inclined ratchet teeth when downward force is applied to the table 30 top. Hence, in this condition of the parts, the table top may be forced down step by step, until the desired height is reached. After which, if desired, the button may be turned to interlock the parts at such heights as indicated in Fig. 8.

To further enable conversion of the table 35 from one form of use to another, various 40 styles and shapes of removable table tops may be provided. Thus by way of example in 45 Figs. 1 and 2, an oval style of table top 27 is shown for direct engagement over the 50 circular fixed table top 12.

The removable top is shown as releasably 55 secured in position on the fixed table top by 60 sliding bolts 28 on the underside of the fixed top adapted to engage with keepers 29, on the underside of the removable top and shown as 65 of segmental form shaped to fit the edge of 70 the fixed top. It will be clear from this illustration, that many different kinds of removable 75 table tops may be combined with the fixed table top to render the device, with the 80 vertical adjustment described, suitable for 85 many different uses. Thus, the particular 90 use of the table may determine both the 95 height and the character of the table top at 100 any given time. For some purposes, the 105 same table top may be used at a number of 110 different levels, but for other purposes, it 115 may become necessary to substitute different 120 styles or shapes of table tops.

The invention it will be seen, is adapted 125 to extension, as well as to solid top tables 130 and in view of the many novel features and uses of the invention, it should be understood that the terms employed herein are used in a descriptive rather than in a limiting 135 sense, except for such limitations as may be required by the state of the prior art. In the case of extension tables or large top tables, it may be desirable to provide weights in the 140 base of the table, substantially as indicated at 145 30 in Fig. 1, which weights may be of lead

set in seats provided for the purpose in the base of the table.

What is claimed is:

1. A combination table, comprising a vertically extensible pedestal, a table top carried thereby, spring means for extending the pedestal to lift the table top and ratchet means for restraining the extension movement of the pedestal, said ratchet means being yieldable to permit contracting adjustment of the pedestal. 70

2. A combination table, comprising a vertically extensible pedestal, a table top carried thereby, spring means for extending the pedestal to lift the table top, ratchet means 80 for restraining the extension movement of the pedestal, said ratchet means being yieldable to permit contracting adjustment of the pedestal and controlling means for said ratchet mechanism operable to fix the ratchet against movement or to permit the ratcheting movement aforesaid. 85

3. A table comprising a hollow base, a post member vertically adjustable in said hollow base, upwardly faced ratchet teeth on said post member, spring means in the hollow base for lifting the post member, a table top carried by the post member, a downwardly faced pawl mounted on the hollow base member for cooperation with the upwardly faced ratchet teeth of the post member and means for controlling said pawl. 95

4. A table comprising a hollow base, a post member vertically adjustable in said hollow base, upwardly faced ratchet teeth on said post member, spring means in the hollow base for lifting the post member, a table top carried by the post member, a downwardly faced pawl mounted on the hollow base member for cooperation with the upwardly faced ratchet teeth of the post member, means for controlling said pawl, including a turn button operable to partly release and hold the pawl in a partly retracted position, the post member having a locking seats and the pawl carrying a locking lug operable to interlockingly engage in one of said locking seats when the turn button is positioned to fully release the pawl. 100

5. A table comprising a hollow base, a post member vertically adjustable in said hollow base, upwardly faced ratchet teeth on said post member, spring means in the hollow base for lifting the post member, a table top carried by the post member, a downwardly faced pawl mounted on the hollow base member for cooperation with the upwardly faced ratchet teeth of the post member, means for controlling said pawl, including a turn button operable to partly release and hold the pawl in a partly retracted position, the post member having locking seats and the pawl carrying a locking lug operable to interlockingly engage in one of said locking seats when the turn button is positioned to fully release the 115 120 125 130 135 140 145 150

pawl and interlocking means for releasably securing the turn button in the position with the parts interlocked as described.

6. A table of the character disclosed, comprising a hollow base, a table top having a pedestal portion slidably received in the hollow base, means for resiliently supporting the sliding pedestal portion in the hollow base, pawl and ratchet mechanism for holding the pedestal portion down to different levels in the hollow base and control means for variously securing said pawl and ratchet mechanism.

7. A combination table comprising a table top, a vertically extensible pedestal for said table top, spring means for extending the pedestal to lift the table top, a spring ratchet in the extensible pedestal for holding the table top down against the extending action of the spring and automatically yieldable to downward pressure on the table top to permit the table top to be lowered by downward pressure on the same and means for locking the pawl against such yielding action and for securing the same in position positively supporting the table top at the desired elevation.

8. In combination, a table having an extensible pedestal made up of relatively telescopic members, one of said members having ratchet teeth and abruptly shouldered locking shoulders adjoining the same, a spring pawl carried by the other member for cooperation with the ratchet teeth and a locking lug for positive interlocking engagement with the locking shoulders aforesaid, said pawl having a ratcheting position in which the pawl will yield to the ratchet teeth and permit relative movement of the two members and a securing position in which the locking lug will interlock with the shoulders and positively hold the two members against relative movement and means for controlling the pawl to enable the ratcheting action or to secure it in the positive holding relation aforesaid.

In testimony whereof I affix my signature.
JOSEPH STEIDL.
